UNITED STATES PATENT OFFICE

THOMAS CARROLL DULIN, OF EASTON, MARYLAND, ASSIGNOR OF ONE-HALF TO HARRY FOX, OF EASTON, MARYLAND

SUBMARINE ESCAPE BUOY

Application filed February 15, 1929. Serial No. 340,231.

This invention relates to an escape buoy for ships, the invention being mainly designed for use with submarines, and the general object of the invention is to make the buoy in the form of a cabin so that the crew and other occupants of the ship can enter the same, with means for releasing the cabin from the ship whereby it will rise to the surface through its own buoyancy.

Another object of the invention is to provide a rudder for the cabin which is automatically moved into operative position when a latch member therefor is retracted after the cabin reaches the surface, said rudder acting to keep the cabin from having erratic movements under the action of the waves and the rudder also acts to keep the cabin from being turned over by the waves.

Another object of the invention is to provide a tank on the ship for receiving the cabin, the tank having a watertight cover, with means for automatically releasing the cover by the escaping movement of the cabin, and means whereby a member of the crew can permit sea water to enter the tank to cause the cabin to pass from the same, such means enabling the operator to enter the cabin and close the door thereof before the water rises high enough in the tank to reach the door.

Another object of the invention is to provide pneumatic means for forcing the cabin from the tank if the water entering the tank should fail, for any reason, to cause the cabin to leave the tank.

Another object of the invention is to provide means for ventilating the cabin without opening the doors or windows thereof, when the same is on the surface and to provide means whereby rockets can be fired from the cabin without danger of flooding the cabin.

This invention also consists in certain other features of construction and in the combination and arrangement of the several parts, to be hereinafter fully described, illustrated in

the accompanying drawings and specifically pointed out in the appended claims.

In describing the invention in detail, reference will be had to the accompanying drawings wherein like characters denote like or corresponding parts throughout the several views, and in which:

Figure 1 is a sectional view through the tank, with the cabin in elevation.

Figure 2 is a plan view of the tank and part of the ship to which the upper end of the tank is connected, with the cover of the tank removed, parts being shown in section.

Figure 3 is a bottom plan view of the cover of the tank and the means for moving the latch means of the cover to releasing position.

Figure 4 is a top plan view of the cover.

Figure 5 is a vertical sectional view through the cabin, showing the same on the surface of the water.

Figure 6 is a section on line 6—6 of Figure 5.

Figure 7 is a sectional view showing a door in the top of the cabin.

Figure 8 is a sectional detail view through the hinged brace.

Figure 9 is a section on line 9—9 of Figure 8.

Figure 10 is a section on line 10—10 of Figure 9.

Figure 11 is a section on line 11—11 of Figure 2.

Figure 12 is a section on line 12—12 of Figure 5.

Figure 13 is a sectional view through the two-way valve for controlling the air supply to the cylinder at the central part of the cabin.

Figure 14 is a detail sectional view showing the means for admitting sea water to the tank to force the cabin from the tank.

In these drawings, the numeral 1 indicates a tank, suitably arranged in a submarine or other vessel, with its upper end fastened to

the walls of an opening made in the deck or other part of the vessel. Figure 1 shows a ring 2 encircling the upper end of the tank and this ring and said end are fastened to the vertical part of an angle flange 3 which is fastened to the deck around the hole. A cover A is provided for the tank and has a pair of depending flanges 4 and 5 which forms a space to receive the upper end of the tank, the ring and a part of the flange 3, with packing means 6 in the space so that when the cover is in closed position a water tight joint is formed between the cover and the tank. The cover is formed of a number of layers 7 of wooden beams 8, the top and bottom beams extending in one direction and the center beam in an opposite direction, as shown in Figure 1 and the beams are connected together and to the struts 9 by the bolts 10. Thus a cover of considerable strength is provided and one which will float when detached from the tank. The cover is connected with the ship by a cable 11 so that it cannot float off when detached.

The cover is fastened in covering position to the tank by the sliding bolts 12 carried by the hangers 13, attached to the bottom of the cover, and said bolts are adapted to engage holes formed in the top of the tank, under the ring 2 and a part of the flange 3, so that the bolts will engage these parts, when projected, thus firmly holding the cover in closing position on the tank. A plurality of substantially triangular shaped members 14 are pivoted to a depending part on the cover, each pivotal pin 15 passing through an upper corner of the wide end of each member, with the lower corner having a slot 16 therein to receive a projection 17 on the inner end of each bolt 12 so that when the small end of each member 14 is swung upwardly the member will retract the bolt. These small ends of the members 14 carry rollers 18 which rest on a plate 19, suspended from the cover by the chains 20 so that when the plate is pushed upwardly all the members 14 will be swung upwardly to retract all the bolts 12 and thus release the cover from the tank and as the cover is buoyant it will float off, though it will remain attached to the ship through means of the chain 11.

Sea water is admitted to the tank through means of a pipe 21 which has its upper end passing through the deck or other part of the ship and its lower end passing into the tank, adjacent the bottom thereof. A valve 22 is located in the tank and is connected with the lower end of the pipe 21 and said valve is provided with an upwardly extending handle 23. Thus by opening the valve water is admitted to the tank, at the bottom thereof. A strainer 24 is placed on the upper end of the pipe 21. A sliding door 25 at one side of the tank provides access

into the interior of the same and base blocks 26 are placed in the bottom of the tank.

A buoy-like cabin B is located in the tank and rests upon the blocks 26, this cabin having vertically arranged fender beams 27 on its sides which carry the rollers 28 for engaging the sides of the tank to guide the cabin in its upward movement through the tank and two pairs of angle irons 29 are attached to the sides of the tank and engage some of the beams 27 so as to facilitate the placing of the cabin in the tank with its door 30 in alignment with the door 25 of the tank.

Thus the occupants of the ship can pass into the tank through the door 25 and into the cabin through the door 30, the latter door opening inwardly. The last person to pass through the doors must close the door of the tank and then open the valve 22, the handle 28 of which is adjacent the door of the cabin, and then the door of the cabin is closed so that water from the tank cannot enter the cabin. The arrangement of the parts will give ample time for the closing of the cabin door before the water rises in the tank to the level of the door. The water entering the tank will cause the cabin to float upwardly and strike the plate 19 and thus cause the plate to retract the bolts 12 to release the cover A. This cover will move off the tank due to its buoyant nature, or if it should stick the upward movement of the cabin would force it off so that the cabin can pass from the tank and rise to the surface.

The central post 31 of the cabin is made in the form of a cylinder and contains a piston 32 which is connected by a rod 33 with a foot piece 34 located exteriorly of the base of the cabin, the rod passing through a packing gland 35 in said base. Pipes 36 connect the upper end of the cylinder with a tank 37 in the cabin containing compressed air and a two-way valve 38 controls the flow of air through this pipe and through a pipe 39 which is connected with the lower end of the cylinder. Thus, if the water flowing into the tank should fail to float the cabin, this valve can be opened to supply air to the top of the cylinder which will force the piston downwardly and thus cause the foot piece and connecting rod to push the cabin upwardly through the tank by the engagement of the foot piece with the bottom of the tank. The parts can be returned to their original position by turning the valve to cause air to flow to the lower end of the cylinder.

The cabin is preferably constructed of wood exteriorly covered with metal and the parts are firmly braced by the braces 40 and that part of the cabin below the water line, when the cabin is floating on the surface, is covered with heavy metal as shown at 41. Brackets 42 are placed on the internal walls of the cabin, adjacent the center thereof, to support braces, one of which is shown in

dotted lines 43 in Figure 5. These braces prevent collapsing of the walls of the cabin when the same is released from a ship at a great depth. After the cabin reaches the surface these braces may be removed and placed in a position where they will not be in the way of the occupants.

Seats 44 are placed on the tank 37 and due to the circular form of the cabin these seats 10 are wider at their backs than at their fronts which facilitates the occupants holding themselves in the seats during violent movement of the cabin when rising to the surface or under the actions of waves. Portions of the 15 tank 37 and the centrally arranged tank 45 may contain floor, water rockets and other articles likely to be used by the occupants. The windows 46 of the cabin are protected by the guards 47. A cap plate 48 is placed 20 on the peak of the cabin roof and has holes 49 in its flanges, whereby cables may be attached to the cabin to moor the same or for other purposes. A stack 50 passes in a water tight manner through the roof and has its 25 lower end supported by one of the brace parts 40 and a ventilating tube 51 passes through the stack and is slidably arranged therein. The upper end of the tube has a cap 52 thereon which fits tight against the upper end of 30 the stack when the tube is in lowered position and adjacent this cap the tube is formed with a hole 53 through which air can enter the tube and thus flow into the cabin when the tube is in raised position. Or the air can 35 pass through the tube from the cabin. This hole is covered by a part of the stack when the tube is lowered so that water cannot enter the cabin through the tube. A rod 54 is attached to the lower end of the tube and is 40 adapted to engage the bayonet slots 55 in the stack to hold the tube in raised position.

A rocket tube 56 also passes through the roof and has a detachable cap 57 on its lower end which is removed to enable a rocket to 45 be placed in the tube. The rocket is lighted through a hole 58 in the side of the tube which is closed by a sliding door 59.

A removable cap 60 covers the upper end of the tube and this cap is hinged to a part 50 of the tube. Of course the cap must make a water tight joint with the tube when closed and a gasket 61 is placed on the cap to permit this. A slotted line 62 is connected with a part of the hinge and a threaded rod 63 55 passes through a packing gland 64 in the roof and has its upper end connected with the link by a pin 65 which engages the slot. Thus by turning the rod by a handle 66 on its inner end the cap can be adjusted to closed 60 or open position. Thus rockets can be fired from the cabin to attract attention of other ships so that the occupants of the cabin can be rescued.

Skids 67 are attached to the bottom of the 65 cabin to facilitate its being moved on a deck

or other place and a pair of arms 68 are hinged to the ends of these skids. A trough shaped member 69 is fastened to the outer ends of these arms and a rudder 70 depends from the central part of the bottom of said member. This rudder acts to keep the cabin from having erratic movements and tends to keep the cabin moving in one direction while on the surface and the weight of the trough shaped member and the water therein will act to keep the cabin from being turned over by the waves striking the cabin from the rudder side thereof and the flat bottom of the member acting against the water will prevent waves coming from the opposite direction 70 overturning the cabin. A two-part brace 71 connects each arm 68 with a part of the cabin. Each section of the brace being formed of channel iron as shown in Figure 10 and the two sections are hinged together as shown 75 at 72.

A spring 73 at the hinge acts to force the brace to open position and thus swing the arms downwardly when the spring plunger 77 is moved downwardly by an occupant of 80 the cabin. This plunger extends through a gland 78 in the roof of the cabin and engages a part of the member 69 when said member is swung against the side of the cabin, as shown in Figure 1. A latch 74 is provided for holding 85 each sectional brace in open position.

A door 75 may be located in part of the roof 90 of the cabin, as shown in Figure 7, with steps 76 leading to the same.

From the foregoing, it will be seen that 95 if a submarine or other ship to which the invention is applied, should sink, it is simply necessary for the occupants to enter the cabin through the doors in the tank and cabin. The valve 22 is opened and the doors closed, so that the water used to release the cabin from 100 the ship, will not flood the ship and the door of the cabin can be closed tight before the water in the tank reaches the same and before there is sufficient water in the tank to cause 105 the cabin to release the cover of the tank. As the cabin strikes the plate 19 and moves the 110 same upwardly, said plate will operate the bolt retracting members so that the cover A is released from the tank and will not interfere with the escape of the cabin from the ship. If the water entering the tank should fail to move the cabin, the compressed air 115 operated means within the cabin can be operated to raise the cabin.

The cabin rises to the surface and when it reaches the surface, the plunger 77 is retracted so as to permit the springs 73 to move the rudder device to operative position. The cabin will float in upright position and if the 120 sea is too rough to open the top door or the windows, the ventilator tube can be raised to admit air to the cabin and permit the foul air to escape. Rockets can be fired from the cabin through the rocket tube without danger 125 130

of getting water in the cabin and without the occupants opening doors to do so. The tail or rudder member will tend to keep the cabin moving with the waves and will prevent the cabin being upset by the waves. After the occupants have been rescued, the cabin can be attached to the rescue ship by cables fastened to the cap plate and the cabin towed to port, and this plate can be used for placing the cabin in the tank by a derrick or the like. The skids will enable the cabin to be moved across a deck or the like without difficulty.

What I claim is:

1. In combination with a ship, a tank therein and opening out through an exterior part thereof, a buoyant cabin in the tank, doors in the tank and cabin whereby occupants can enter the cabin from the ship, means for admitting sea water into the tank by an occupant entering the cabin and after the door of the tank is closed, said water causing the cabin to pass from the tank, a watertight buoyant cover for the tank, latch means for holding the same in closed position, means operated by the movement of the cabin in the tank for releasing the latch means, a rudder member pivoted to the lower part of the cabin and resting against the cabin when the cabin is in the tank, a latch for holding the rudder in this position, means for automatically swinging the member to operative position when the latch is retracted and a trough carried by said member above the rudder thereof.
2. In combination with a ship, a tank therein and opening out through an exterior part thereof, a buoyant cabin in the tank, doors in the tank and cabin whereby occupants can enter the cabin from the ship, means for admitting sea water into the tank by an occupant entering the cabin and after the door of the tank is closed, said water causing the cabin to pass from the tank, a water-tight buoyant cover for the tank, latch means for holding the same in closed position and means operated by the movement of the cabin in the tank for releasing the latch means, such means comprising pivoted members connected with the latch means, rollers on the lower ends of said members, a plate, flexible members for suspending the plate from the cover and a part on the roof of the cabin for engaging the plate for forcing it against the pivoted members when the cabin moves in the tank for causing said members to release the latch means.
3. In combination with a ship, a tank therein and opening out through an exterior part thereof, a buoyant cabin in the tank, doors in the tank and cabin whereby occupants can enter the cabin from the ship, means for admitting sea water into the tank by an occupant entering the cabin and after the door of the tank is closed, said water causing the cabin to pass from the tank, a watertight

buoyant cover for the tank, latch means for holding the same in closed position, means operated by the movement of the cabin in the tank for releasing the latch means, a rudder member pivoted to the lower part of the cabin and resting against the cabin when the cabin is in the tank, a latch for holding the rudder in this position and means for automatically swinging the member to operative position when the latch is retracted.

In testimony whereof I affix my signature.
THOMAS CARROLL DULIN.
